UNITED STATES PATENT OFFICE.

ROBERT W. ELLIOTT, WARREN A. JOHNSTON, AND LEWIS J. BUERKLE, OF DAYTON, OHIO, ASSIGNEES TO THE DAYTON ENGINEERING LABORATORIES COMPANY, OF DAYTON, OHIO, A CORPORATION OF OHIO.

BRUSH HOLDER.

Application filed July 13, 1921. Serial No. 484,426.

To all whom it may concern:

Be it known that we, ROBERT W. ELLIOTT, WARREN A. JOHNSTON, and LEWIS J. BUERKLE, citizens of the United States of America, residing at Dayton, county of Montgomery, State of Ohio, have invented certain new and useful Improvements in Brush Holders, of which the following is a full, clear, and exact description.

10 This invention relates to improvements in brush supporting devices for electric machines having commutators.

15 It is among the objects of the present invention to eliminate brush squeaks or any other undue noises caused by the brushes.

20 A further object is to provide a brush structure that will cause certain portions of the contacting surface of the brush to engage with the commutator at different speeds thereof.

25 Further objects and advantages of the present invention will be apparent from the following description, reference being had to the accompanying drawings, wherein a preferred embodiment of the present invention is clearly shown.

30 In the drawings, Fig. 1 is a side elevation of the brush and its supporting elements.

35 Fig. 2 is a top plan view of the brush and brush holder.

Figure 3 is a view similar to Fig. 1 but showing the different positions of the brush when the spring plate support is distorted.

40 Fig. 4 is an end view of the brush support, the dotted lines showing the brush in its displaced positions, due to an imperfect commutator.

Fig. 5 is an end view of an electric machine with the brushes shown in relative positions.

45 Fig. 6 is an enlarged view of the device showing the "toe" or front edge of the brush engaging with the commutator.

Fig. 7 is a view similar to Fig. 6 but showing the middle of the brush engaging with the commutator, and

50 Fig. 8 is another view similar to Fig. 6 showing the "heel" or rear edge of the brush engaging the commutator.

Referring to the drawings, the numeral 20 designates a supporting arm, having ears 21 and 22 provided with holes through which the fulcrum pin 23, carried by the plate

24, is adapted to project, the pin forming 55 a pivotal support for the arm 20.

Interposed between the ears 21 and 22 and secured to the supporting arm 20 is the spring plate 25 which is provided with an angular portion 26 to which is secured 60 the brush 27 by means of screws 28 and nut 29. The arm 20 is provided with an extended portion 30 lying in alinement with and adjacent to the spring plate 25. This 65 extended portion 30 has a hump 31 provided with a screw threaded hole 32 to which the lead wire is adapted to be screwed.

Another projection 33 extending from the 70 ear 22 has a hook portion 34 against which one end of the coil spring 35 abuts while the opposite end of the spring is anchored on a stud 36 carried by the plate 24. This 75 spring tends to hold the brush 27 against the commutator 37.

Referring to Fig. 3 it may be seen that the brush element 27 may be moved into different positions, as shown in dotted lines, due to the yieldability of the spring plate 80 25 on which the brush is mounted. This 85 spring plate 25 will not only allow movement of the brush in this direction, which may be termed the commutator peripheral direction, but also as shown in Fig. 4 by the dotted lines which might be termed the 90 commutator longitudinal direction.

The flexing properties of the flat plate or spring 25 depend chiefly on the metal used therein and the size of the spring. The plate lies in a plane tangential to the commutator. Relatively stiff springs yield less 95 to the frictional drag on the brush and reduce the rolling action of the brush end on the commutator.

In the commercial production of electric 95 machines including commutators and brushes, certain imperfections in workmanship will occur that will tend to cause imperfect contact between the said commutators and brushes, resulting in undesirable 100 squeaks and noises. This condition will also cause undue sparking and poor commutation, thereby greatly affecting the efficient operation of the machine. However in the present structure, if any imperfections in workmanship occur, the brush will still be held in substantially perfect contact with the commutator due to the yieldabil- 105

ity of its spring carrier plate 25 and the action of the spring 35 to force the brush into good engagement with its commutator.

In operating commutators in electric machines under certain circumstances it has been found that due to heat the commutator has become distorted, thereby causing poor engagement of the brushes, affecting commutation and causing squeaky noises. In using the present brush structure with faulty commutators it has been found by experiment that the yielding brush mounting together with the effect of the tension spring 35 will tend to cause the brush to ride evenly on the commutator thus substantially overcoming the ill effects of commutator distortion and providing good commutation and eliminating noises.

20 It is also well known in the art that the use of a very narrow brush, or, more specifically, a brush slightly wider than the insulation between the commutator bars, is desirable in order to obtain good commutation and efficient machine operation. In the present invention the effect of a narrow brush is obtained by the use of a comparatively wide brush in the following manner. The brush 27 and its component supporting elements are so positioned that when the machine is idle only the "toe" or front portion of the brush marked "A" in Figs. 6, 7, and 8 engages with the commutator. The "middle" and "heel" portions marked "B" and "C" respectively do not engage with the commutator. This provides a narrow brush contact while using a comparatively wide and mechanically strong brush.

40 The surface "A" will ride on the commutator when it is not in motion and during a certain range of slow rotation of the commutator. As soon as the commutator is driven at a higher rate, or what might be termed a normal operating speed, the frictional drag or pull of the commutator on the brush will tend to move the said brush in the direction of commutator rotation, indicated by the arrow, against the action 45 of the spring plate 25 which will now be distorted. This rocking or moving of the brush in the said direction will tend to cause its intermediate end surface or zone "B" to ride on the commutator, thus again 50 providing only a comparatively narrow operative brush surface.

As the speed of the commutator increases above normal, the brush will be drawn further in the direction of commutator rotation thus causing the brush to ride on its "heel" or "C" surface as shown in Fig. 8. Due to the action of the spring plate 25, the brush will assume its previous positions as the speed of rotation of the commutator 65 is reduced.

While the form of mechanism herein shown and described constitutes a preferred form of embodiment of the invention, it is to be understood that other forms might be adopted, all coming within the scope of the 70 claims which follow.

What we claim is as follows:

1. In a dynamo electric machine the combination with the commutator thereof and a brush for engaging the commutator; of 75 means for holding said brush in engagement with the commutator so that different portions thereof will engage said commutator under varying speeds.

2. In a dynamo electric machine the combination with the commutator thereof and a brush for engaging the commutator; of 80 means for yieldingly maintaining the brush in engagement with the commutator while at the same time permitting different portions of the brush to engage said commutator under varying speeds.

3. In a dynamo electric machine the combination with the commutator thereof and a brush for engaging the commutator; of 85 means for yieldingly maintaining only the toe portion of the brush in engagement with the commutator while said commutator is rotating at relatively low speeds.

4. In a dynamo electric machine the combination with the commutator thereof and a brush for engaging the commutator; of 90 means for yieldingly maintaining only the middle portion of the brush in engagement with the commutator while said commutator is rotating at relatively normal speed.

5. In a dynamo electric machine the combination with the commutator thereof and a brush for engaging the commutator; of 105 means for yieldingly maintaining only the heel portion of the brush in engagement with the commutator while said commutator is rotating at relatively high speed.

6. In a dynamo electric machine the combination with the commutator thereof and a brush for engaging the commutator; of a 110 yieldable support for the brush, permitting the engaging surface thereof to rock side-wise upon the commutator when said commutator is in motion; and means for yieldingly urging said support toward the commutator.

7. In a dynamo electric machine the combination with the commutator thereof and a brush for engaging the commutator; of a 120 yieldable support for the brush, permitting the engaging surface thereof to rock edge-wise upon the commutator when said commutator is in motion; and means for yieldingly urging said support toward the commutator.

8. In a dynamo electric machine the combination with the commutator thereof and a brush for engaging the commutator; of a 125 yieldable support for the brush, permitting 130

the engaging surface thereof to rock side-
wise and edgewise upon the commutator
when said commutator is in motion; and
means for yieldingly urging said support
5 toward the commutator.

9. In a dynamo electric machine the com-
bination with the commutator thereof and a
brush for engaging the commutator; of a
leaf-spring adapted to carry said brush; a
10 pivotal support having one end of the leaf-
spring attached thereto; and a spring as-
sociated with said support for yieldingly
urging the leaf-spring toward the commu-
tator for causing the brush to engage there-
15 with.

10. In a dynamo electric machine, the
combination of a support; a commutator ro-
tatably mounted thereon; a brush having
endwise engagement with the commutator;
20 and means for supporting said brush, com-
prising a flexible flat member pivotally
mounted on the support with a flat face
thereof toward the commutator, means
yieldingly urging the free end of the mem-

ber toward the commutator, and means for 25
securing the brush to the free end of the
member.

11. In a dynamo electric machine, the
combination of a field frame; a rotor mount-
ed therein; a cylindrical commutator on one 30
end of the armature; a brush having end-
wise engagement with the commutator; a
flexible flat member supporting the brush
and lying in a direction substantially tan-
gential to the commutator and having one of 35
its ends pivotally mounted on the field
frame, the free end being bent out of the
said tangential direction and fastened to the
brush; and means for yieldingly urging the
flat member toward the commutator. 40

In testimony whereof we hereto affix our
signatures.
